BRADFORD W. NICHOLS, OF PHENIX VILLAGE, RHODE ISLAND.

Letters Patent No. 69,472, dated October 1, 1867

IMPROVEMENT IN PICKERS FOR LOOMS.

The Schedule referred to in these Letters Patent and making part of the same.

TO ALL WHOM IT MAY CONCERN:

Be it known that I, BRADFORD W. NICHOLS, of Phenix Village, in the county of Kent, and State of Rhode Island, have invented a new and useful Improvement in Loom-Pickers; and I do hereby declare that the following is a full, clear, and exact description thereof, which will enable others skilled in the art to make and use the same, reference being had to the accompanying drawings, forming part of this specification, in which—

Figure 1 is a front view of my improved picker.

Figure 2 is a side view with a part of the raw-hide covering removed

Similar letters of reference indicate like parts.

This invention relates to a new and useful improvement in the picker of a loom, and consists in making the shell or casing and the binder of the picker of raw hide, and securing it to the staff by flanges on each side in such a manner that it cannot slip out of place when put in running order, nor break, nor allow the filling to come out; and when the filling is worn out it may be easily replaced.

A is the staff, to which is fastened a raw-hide picker-shell or case *a* by means of a raw-hide binder, *b*, which binds the neck of the picker to the staff, and is secured with rivets *d d*, as shown in the drawings. The picker-case is made in the shape of a loop by bending the raw hide on a proper form when made soft by soaking; and between the ends *s s*, forming the neck by which it is attached to the staff, is placed a strip of hide or leather, *c*. The two ends *s s* and the strip *c* are fastened with rivets *e e*. The picker-case laps over the sides of the staff with projections *h h*, which shoulder upon the staff and keep the picker in place, as shown in fig. 2. The picker-filling *g* is made of leather, India rubber, cork, or any suitable material for striking the shuttle, and is fitted in the loop of the case under a shoulder, *i*, in the hide at the edges of the upper side.

I claim as new, and desire to secure by Letters Patent—

The combination of the picker-staff and binder *b* with a raw-hide case, *a*, the case having laps *h* projecting over the sides of the staff, and a shoulder, *i*, in the hide to hold the filling *g* in place, substantially as described.

BRADFORD W. NICHOLS.
